UNITED STATES PATENT OFFICE.

GUSTAV E. ANDERSON, OF SOUTH BEND, INDIANA.

COMBINATION AIR-VALVE AND PRIMER FOR INTERNAL-COMBUSTION ENGINES.

1,329,354.

Specification of Letters Patent.

Patented Feb. 3, 1920.

Application filed August 27, 1917. Serial No. 188,365.

To all whom it may concern:

Be it known that I, GUSTAV E. ANDERSON, a subject of the king of Sweden, but a declarant of intention of becoming a citizen of the United States, residing in the city of South Bend, St. Joseph county, Indiana, have invented certain new and useful Improvements in Combination Air-Valves and Primers for Internal-Combustion Engines, 10 of which the following is a specification.

My invention relates to a combination device for automatically supplying pure air to the explosion chamber of an internal combustion engine and for automatically priming the motor.

An object of my invention is the production of the device of the character described which is cheap, easily constructed and quickly applied to an internal combustion 20 engine. Another object is the production of an automatic air inlet valve of relatively small area and size as compared with the regular fuel inlet valve to supply pure air to the explosion chamber of the motor on 25 each suction stroke of the piston and for the full stroke or movement thereof for enhancing the motor flexibility, increasing the power of the engine, effecting a more rapid acceleration of the engine, and for minimizing the engine vibration when in operation.

Another object is the production of a priming device in combination with an air inlet valve for an internal combustion engine which automatically opens on the suction stroke of the engine piston, whereby the priming fuel is drawn into the engine cylinder and by the piston movement and thoroughly vaporized into a combustible 40 mixture. Other objects of my invention are hereinafter described.

The preferred embodiment of my invention is well illustrated in the accompanying drawings in which Figure 1 is a view in elevation of the invention; and Fig. 2 is a section in elevation through Fig. 1.

Similar numerals of reference refer to similar members and parts of members throughout the several views on the drawings.

On the drawings, the numeral 1 indicates a body member detachably joined to a plug member 2 by the screw thread connection at 3, the member 2 being rigidly screwed 55 against a shouldered portion 4 interiorly of

the body member 1. The numeral 5 indicates a valve chamber formed interiorly of member 1 and registering and communicating with a complementary chamber 6 formed in the end of the plug member 2, the former chamber being provided with a conical valve seat 7 upon which the valve 8 is arranged.

The numeral 9 indicates a valve stem traversing the cylindrical supply chamber 10 and upon which the valve 8 is mounted, said valve stem being slidably arranged in the guide aperture 11 which is formed longitudinally of the extension 12 of the body member 1. Numeral 13 indicates a valve stem extension projecting beyond the guide portion 12 and upon which the valve spring 14, adapted to hold the valve 8 upon its seat, is mounted, said spring being seated against the opposed washers 15 and 16. The numerals 17, 17 indicate nuts screw threaded upon the stem extension 13 for confining the spring upon the stem and for adjustment of the spring tension.

Numeral 18 indicates a screw threaded end 80 of the plug member 2 and adapted to be screwed into the engine cylinder wall 19 to effect permanent communication between the engine cylinder combustion chamber and the air and fuel conduit 20, the latter being 85 in permanent communication with the chambers 5 and 6. The numeral 21 indicates a fuel cup or receptacle having a cylindrical portion 22 which is screw threaded upon the body member 1 at 23. Numerals 24 and 25 indicate oppositely disposed lateral apertures formed in the body member extension 12 adjacent the bottom of the cup 21 and adapted to admit pure air or liquid fuel to the supply chamber 10.

Numeral 26 indicates a knurled portion on the exterior of the body member 1, and numeral 27 indicates a polygonal portion of the plug member 2 for wrench application.

In operation, as an air inlet valve, the 100 valve 8 is opened and pure air is drawn past same through the apertures 24 and 25 on each suction stroke (being the fuel intake stroke) of the engine piston, whereby a quantity of pure air is introduced to the 105 combustion chamber of the engine cylinder for the full suction stroke of the piston, said valve closing automatically upon the completion of the piston stroke. For priming the engine the cup 21 is filled with gasoline, 110

2
or other suitable liquid fuel, the chamber 10 being filled simultaneously through the apertures 24 and 25, the fuel being held within said cup and chamber until the suction stroke 5 of the engine piston is started in any manner, whereupon the valve 8 opens slightly and the fuel passes into the engine cylinder through conduit 20, being thoroughly vaporized into a combustible mixture thereby.

10 I claim:

1. A device of the character described comprising coöperative body and plug members rigidly joined together, said members having intercommunicating parts forming 15 a valve chamber, said valve chamber having an outlet which is permanently open, and said body member having a reduced upward extension portion which is provided with a fluid supply chamber and a valve stem guide bore above said chamber, said supply chamber having an inlet opening adjacent the upper end thereof; a spring controlled valve in said first mentioned chamber, said valve having a stem which traverses said supply 20 chamber and is slidably arranged in said guide bore; and a separate piece fuel recep- 25

tacle mounted upon said body portion and arranged around said supply chamber inlet.

2. A device of the character described comprising coöperative body and plug members rigidly joined together, said members having intercommunicating parts forming a valve chamber, said valve chamber having an outlet adapted to be placed in permanent communication with the explosion chamber 30 of an internal combustion engine, and said body member having an upward extension portion which is provided with a fluid supply chamber and a valve stem guide bore above said chamber, said supply chamber 35 having an air inlet opening adjacent one end thereof; a conical spring controlled valve in said valve chamber, said valve having a stem which traverses said supply chamber and is slidably arranged in said guide bore; 40 and a fuel cup mounted upon said body extension portion and arranged around the inlet opening of said supply chamber. 45

In testimony whereof I have hereunto affixed my signature this 24th day of August, 1917.

GUST. E. ANDERSON.
